UNITED STATES PATENT OFFICE.

GEORGE B. SEMLEY, OF KENOSHA, WISCONSIN.

SHEET-TURNER.

1,393,400.

Specification of Letters Patent.

Patented Oct. 11, 1921.

Application filed May 18, 1920. Serial No. 382,427.

To all whom it may concern:

Be it known that GEORGE B. SEMLEY, a subject of the King of Great Britain, and resident of Kenosha, in the county of Kenosha, and State of Wisconsin, have invented certain new and useful Improvements in Sheet-Turners; and I do hereby declare that the following is a full, clear, and exact description thereof.

10 My invention relates to new and useful improvements in devices for turning sheets, for instance the leaves of a music book or sheet music.

It is the principal object of this invention 15 to provide a simply constructed and readily operated leaf turner which can be used in connection with various kinds of musical instruments and music stands.

An additional object of the invention is to 20 provide a device of this character which can be easily actuated by one foot of the player, thus permitting him to perform without interruption.

With these general objects in view, the invention 25 consists in the novel features of construction, combination and arrangement of parts which will be hereinafter more particularly described and claimed.

In the accompanying drawings, Figure 1 30 represents an end view of a piano having my improved sheet turner mounted thereon.

Fig. 2 is an enlarged detail end view, partly in section, of the device.

Fig. 3 is an enlarged detail side elevational view, partly in section, of the structure shown in Fig. 2.

Fig. 4 is a detail section taken substantially on the plane of the line 4—4 of Fig. 2, and Fig. 5 is a substantially horizontal section 40 on the plane of the line 5—5 of Fig. 1.

As shown in the drawings, and especially in Fig. 1, the invention can be mounted upon a piano P, in which instance a portion of the actuating mechanism extends behind and 45 beneath the instrument as shown. To use the principles of the invention in connection with music stands and the like, it would obviously be necessary to notify the illustrated embodiment to a certain extent. However,

50 it is within the scope of the present invention to make such changes in the form and proportions of the different parts as to accommodate the device for use where necessary or desirable.

55 The music rest R of the piano on which the music M stands has a plurality of turn-

ing arms 1 depending in front thereof from a suitable bracket plate 2, this plate being carried by a stationary head block 3. The head block 3 is secured upon the top of the piano P by means of a foot 4, and one side thereof has a longitudinally and substantially horizontally extending key-seat 5. A 60 slideable head block or carriage 6 having a dovetail 7 disposed in said keyway 5 is movable laterally on the stationary head block. 65

Each of the turning arms 1 is provided intermediate its ends with a pivot ear 8 by which the same may be fulcrumed to the bracket plate 2. One of the ends of each 70 arm 1, that is to say the upper end thereof when the same are in vertical inactive position, is enlarged as at 9 to provide a counter-balance, whereby when the arm is moved to one side of a vertical line, it will be shifted 75 to a substantially horizontal position by the action of gravity. A portion of each bearing in which the pivot ears 8 are mounted has a shoulder 10 against which the arms 80 abut when in vertical inactive position, a second shoulder 11 being provided to limit the downward swinging movement of the counter-balanced portions and to retain the arms substantially horizontal when in active position. 85

In so far as the present invention is concerned, the number of turning arms 1 which are pivoted on the bracket plate 2 is immaterial, but for each of said arms a latch bar 12 is provided, these latch bars being pivoted 90 substantially midway their ends upon a pivot rod 13 carried by the stationary head block 3. The portions of the blocks 12 to one side of the pivot engage the undersurface of said head block 3 and when the carriage 6 is in its outermost position with its outer end flush with the similar end of the stationary head block 3, the portions of said latch bars 12 on the opposite side of the fulcrums thereof engage the undersurface of said carriage. It will be seen, however that as the carriage 6 is moved rearwardly, the latch bars 12 will be successively freed from engagement with the former. The counter-balanced ends 9 of the arms 1 95 are preferably curved or arcuate as at 14, and when said arms are in locked vertical position, each of these curved parts is disposed in an arcuate groove 15 in the latch bars 12. 105

Inasmuch as the turning arms will remain in vertical position regardless of the coun-

ter-balanced ends 9 unless initially urged toward a horizontal position, provision is made for imparting a starting motion to each of the turning arms as it is necessary 5 to bring them into play for turning the music leaves L. For this purpose each of the latch bars 12 has a longitudinally extending release finger 16 normally slidably disposed in a guide groove 17 in the carriage 6. The 10 forward end of the carriage adjacent this groove 17 has a turned up trip finger 18 which, as it is successively brought into contact with the release fingers 16, forcibly urges the same upwardly. In other words, 15 the latch bar 12 which carries this finger is kicked into the position shown in dotted lines in Fig. 2 with the result that the turning arm 1 located in engagement therewith is given an initial motion toward a horizontal 20 position. The weight of the counterbalance 9 thereof continues the movement of the arm 1 until it strikes the stop 11. Leaf springs 19 are carried by the bracket plate 2 and one is located in position to be engaged 25 behind each turning arm 1 when in vertical position. When the turning arms 1 are locked by the latch bars 12, these springs 19 are compressed so that they will exert their tension to aid the movement of 30 the latch bars in urging the turning arms toward said horizontal position.

The carriage 6 is moved rearwardly to successively actuate the latch bars and to release the turning arms by means of a pawl 35 and ratchet 20 and 21 respectively, the latter being formed on the rear end of a connecting rod 22 with which the carriage 6 is pivotally connected. The pawl on the other hand is carried by a bell-crank 24 fulcrumed 40 on a bracket 25 secured to the rear of the piano P. One of the arms of the bell-crank 24 has a link 26 connecting the same with one end of a lever 27 extending beneath the piano P. The forward end of this lever is 45 provided with a foot pedal 28 so that upon each downward movement of the forward end of the lever 27, the link 26 will be moved upwardly and the bell-crank 24 rocked. Return springs 29 move the link 26 and the 50 parts carried thereby to normal inactive position.

In using the invention the music M is placed on the rest R and the turning arms 1 are disposed between the leaves L thereof, 55 said turning arms being then located in their inactive vertical positions with their upper ends locked by the latch bars 12. Likewise

the carriage 6 is positioned at its outermost limit with its front end flush with the similar and the stationary head block 3. Thus 60 upon each depression of the foot pedal 28, the carriage is moved rearward a predetermined distance to expose the latch bars 12 in their regular order, and as each latch bar is kicked out of normal horizontal position by 65 the trip 18, the turning arm 1 thereby will be released and the music leaves L turned.

I claim:

1. In a mechanism of the class described, a normally inactive turning arm pivoted 70 intermediate its ends, a weight on one of said ends, a pivoted latch bar having a groove receiving a portion of the arm to retain the same in inactive position, and means for rocking the latch bar to release the arm and to move the same toward an active position, the weight completing the movement of the arm from its inactive to its active position. 75

2. In a mechanism of the class described, 80 a normally inactive turning arm pivoted intermediate its ends, a weight on one of said ends, a pivoted latch bar having a groove receiving a portion of the arm to retain the same in inactive position, a 85 slideable member normally holding said latch bar to retain said arm in inactive position, means for moving said slideable member to release said latch bar and means carried by 90 said slideable member for positively rocking said latch bar when released to move the arm toward an active position, the weight completing the movement of the arm from its inactive to its active position. 95

3. In a mechanism of the class described, 100 a normally inactive pivoted turning arm, means for supporting the same above the music rest of a piano, a slideable member for holding the same in substantially vertical position, a reciprocable rod attachable to the back side of a piano, and connected with said slideable member and actuatable to move said slideable member to release said turning arm, a pedal operable by the player while 105 playing and operatively connected with said reciprocable rod to actuate the same to release said turning arm, and means for moving the latter to substantially horizontal position when so released. 110

In testimony that I claim the foregoing I have hereunto set my hand at Kenosha, in the county of Kenosha and State of Wisconsin.

GEORGE B. SEMLEY.
